UNITED STATES PATENT OFFICE.

HALL H. HOLDAWAY, OF LOS ANGELES, CALIFORNIA.

DESIGN FOR AN AUTOMOBILE-TIRE.

47,135.

Specification for Design.

Patented Mar. 23, 1915.

Application filed February 9, 1915. Serial No. 7,128. Term of patent 14 years.

To all whom it may concern:

Be it known that I, HALL H. HOLDAWAY, a citizen of the United States, residing at Los Angeles, in the county of Los Angeles and State of California, have invented a new, original, and ornamental Design for an Automobile-Tire, of which the following is a specification, reference being had to the accompanying drawing, forming part thereof.

Figure 1 is a plan view of a portion of the tread of an automobile tire, showing my new design. Fig. 2 is a transverse sectional view

through the said automobile tire, taken upon the line 2—2 of Fig. 1.

I claim—

The ornamental design of an automobile tire, as shown.

In testimony whereof, I have hereunto set my hand, in presence of two witnesses.

HALL H. HOLDAWAY.
